By Atty. A. Dubois

UNITED STATES PATENT OFFICE.

WILLIAM H. PRIDE, OF SPRINGFIELD, ILLINOIS.

DESIGN FOR A FINGER-HAMMER FOR MUSICAL INSTRUMENTS.

SPECIFICATION forming part of Design No. 32,952, dated July 17, 1900.

Application filed March 14, 1900. Serial No. 8,679. Term of patent 7 years.

To all whom it may concern:

Be it known that I, WILLIAM H. PRIDE, a citizen of the United States, residing at Springfield, in the county of Sangamon and State of Illinois, have by my own industry, genius, efforts, and expense invented and produced a new, useful, and original Design for a Finger-Hammer for Musical Instruments, of which the following is a specification, reference being had to the accompanying drawing, forming part of this application.

My said design resides and is embodied in a finger-hammer having the shape or configuration shown in the drawing and hereinafter described.

My said design embraces three elements—viz., an annular thimble, a curved rod ex-

tending outward from said thimble, and a hammer of approximately-ovoidal form at the extremity of said rod remote from said thimble, all arranged substantially as shown.

That which I have invented and produced, and that which I desire to secure by Letters Patent, is—

The design for a finger-hammer for musical instruments, substantially as herein shown and described.

In witness whereof I have hereunto subscribed my name at Springfield, Illinois, this 14th day of February, A. D. 1900.

WILLIAM H. PRIDE.
